POWER OPERATED TYPEWRITER

Frederick W. Schremp, Elmira, N. Y., assignor to
 Remington Rand Inc., New York, N. Y., a corporation of Delaware

Application June 25, 1949, Serial No. 101,450

18 Claims. (Cl. 197—17)

1

This invention relates to power operated typewriters and particularly to a typewriter having the type actions actuated by a continuously driven power roll operated by an electric motor.

The typing and other parts of a typewriter usually operated by manual actuation of the key levers are power actuated according to the present invention from the continuously rotating power driven roll by selective key lever operation of the power operating mechanism.

The power operating mechanism of the present invention has a plurality of spaced parallel power arms with eccentrics rotatably mounted thereon for peripheral engagement with the power driven roll for moving the power arms so that one end of an operated power arm will engage a typing or other device and produce a complete operation thereof for each revolution of the eccentric. The operation of the power arm and eccentric by the power driven roll is controlled by manual operation of the key levers to selectively operate the desired typing and other device in the usual manner from the typewriter keyboard. The key levers control the operation of a trigger for each power arm. Each trigger is formed to engage and operate a trip member controlling the rotation of the eccentric. When a key lever is manually operated according to the present invention, it will engage the trigger with the trip member for the corresponding power arm and disengage the trip member from the eccentric so that it may have limited movement immediately upon release of the trip member to engage the continuously rotating power driven roll. As soon as the periphery of the eccentric engages the continuously rotating power roll it will rotate with the power roll and by reason of its eccentric mounting on the power arm will cause the power arm mounted on a pivot at one end, to rotate on this pivot so that the opposite end will move back and forth according to the eccentricity of the eccentric. The trigger and trip member cooperate to control the rotation of the eccentric so that for each operation of a key lever, the eccentric is released for operation by the power driven roll through one revolution only. The eccentric is positioned so that the portion of the periphery having the shortest radius from the axis of rotation is directed toward the power driven roller in the position of rest or inoperative position of the power arm when the trip member is engaged with the eccentric to normally hold it against rotation.

The eccentric and operation of the power arm is controlled by the trip member and trigger through key lever operation so that the eccentric

2

or power arm will be moved slightly to engage the periphery of the eccentric with the power roller as soon as a key lever is manually depressed. The power roller will then rapidly rotate the eccentric and move the power arm on its pivot so that the free end will be moved to engage and operate a typing or other device through approximately one-half of the rotation of the eccentric by the power driven roll from the point of shortest radius of the eccentric from its center to the point of longest radius. This produces movement of the power arm in one direction to secure the power operation of the typing or other device after which the power arm returns to its starting position when the trip member will engage and latch the eccentric in a position where it becomes disengaged from the power roll in a position ready to start a subsequent operation of the power arm for a repeated operation of the typing or other device.

Means are provided by the invention through the cooperation of the trigger and trip mechanism with the eccentric and power arm to prevent more than one operation of the typing or other device by a power arm for each depression of a key lever.

The invention provides a fulcrum bar for pivotally mounting all of the power arms with manually operated means for adjusting the position of the fulcrum bar in controlling operation of the typing or other devices by the power arms for varying the extent and power applied to the operation of typing or other devices. By varying the power applied to the typing or other devices, particularly the type bars, the force of impact of the type with the platen may be varied within a desired range. This is principally useful in producing multiple copies of typewritten matter.

The end portion of each power arm positioned to engage a typing or other device is adjustable relative to the eccentric and pivot for the power arms. This construction provides for adjustment of each power arm relative to the others for obtaining a uniform impact or variation in the force of impact of each type bar with the platen. It also provides for the desired movement of the power arm in operating the other devices such as the carriage return, case shift, ribbon feed, etc.

The operation of the power arm by the eccentric as provided by the present invention secures an improved operation in which the power roll is subjected to a minimum amount of wear due to the eccentrics being freely rotatable on the power arms for free rotation during contact with the power driven roll. The invention also provides

for the construction of a power arm, eccentric and trip mechanism as a unit so that a plurality of either of these units may be readily installed and adjusted to secure the desired operation of the type actions and other key lever actuated devices of the typewriter.

In the drawings:

Fig. 1 shows portions of a typewriter in perspective to illustrate a type action, power driven roll, the power operating assembly for two type actions and the controls operated by the key levers, portions being broken away and shown in cross-section for convenience in illustrating the invention.

Fig. 2 is an enlarged vertical cross-section through a typewriter with portions omitted and other portions shown in cross-section and broken away illustrating a type action and the key lever actuated trigger and trip mechanism on one power arm in side elevation in the position of rest with the mechanism used for operating the ribbon vibrator.

Fig. 3 is a fragmentary vertical cross-section similar to Fig. 2 showing only the power operating mechanism and the adjusting means for varying the position thereof with the parts shown at the opposite limit of adjustment from that shown in Fig. 2, the power arm having the end for engaging the type bar bell crank arranged at the greatest distance away from the bell crank so that the period during which the power arm is engaged with the bell crank is less than with the parts adjusted in the position shown in Fig. 2.

Fig. 4 is a fragmentary front elevation of a portion of the typewriter showing the lever for adjusting the power arm assembly to change the impact pressure of the type bars on the platen.

Fig. 5 shows an enlarged diagrammatic illustration of the power driven roll and power arm assembly illustrating in full lines the position of rest or starting position, designated No. 1, of a power arm, trip mechanism, trigger assembly and type bar, while the dot and dash line position shown illustrates a second or No. 2 position of the power arm assembly resulting from depressing the type bar to operate the trigger and trip mechanism for releasing the eccentric to cause the periphery thereof to engage the power driven roll with a slight downward movement of the power arm for starting the movement of the power arm by the power driven roll to secure the operation of a type action or similar device.

Fig. 6 is a view similar to Fig. 5 illustrating in dot and dash lines another position in the cycle of operation of the power arm and eccentric designated No. 3, showing the position at which the trip lever is about to disengage the trigger with the trigger shown in the position in which it is held during manual depression of a key lever, the power arm having begun its operating stroke through the operation of the eccentric by the power driven roll. The full line position in Fig. 6 shows the power arm and trip mechanism in the No. 4 position in which the eccentric has moved 180 degrees from the No. 1 position shown in Fig. 5, so that the portion of greatest radius has moved around until it is in engagement with the power driven roll and has moved the power arm upwardly to the limit of its upward pivotal movement from the No. 1 and 2 positions shown in Fig. 5 to secure a complete operation of a type action or other actuated part of a typewriter.

Fig. 7 shows a modified form of power arm eccentric, trip member and trigger construction from that shown in the preceding figures in verti-

cal transverse cross-section with the power arm, eccentric and trigger mechanism shown in elevation diagrammatically with the parts in the position of rest or starting position herein described as No. 1 position, as indicated in connection with the showing in Fig. 5.

Fig. 8 is a diagrammatic view of the power operating mechanism, as shown in Fig. 7, with the parts shown in the No. 2 position, which is the position showing depression of a key lever to operate the trip mechanism and release the eccentric for engaging the power driven roll.

Fig. 9 shows the No. 4 position of the modified form of Fig. 7, with the eccentric having its longest radius extending downwardly from its axis and engaging the periphery of the power driven roll.

Fig. 10 is a view of the structure shown in Figs. 7 to 9 showing the eccentric at a point where it has nearly completed one revolution of operation by the power roll from the position shown in Fig. 7 after manual operation of a type bar, in which the type bar and trigger mechanism is shown in the depressed position for illustrating how the trip and trigger mechanism cooperate to prevent a repeat operation of the type bar during one depression of a key lever.

Fig. 11 is a perspective showing a power arm, eccentric and trip lever mechanism constructed as shown in Fig. 7, in disassembled separated relation to illustrate details of construction and assembly of the eccentric on the power arm.

Fig. 12 is a view similar to Fig. 7 illustrating another modified form of power arm and trip lever mechanism showing the parts in the position of rest or No. 1 position.

Fig. 13 is a view similar to Fig. 7 illustrating another modified form of power arm, eccentric and trip lever construction in the position of rest or starting position referred to herein as the No. 1 position.

Fig. 14 is a view looking at the opposite side of the power arm from that shown in Fig. 13.

Fig. 15 shows a modified form of trigger in side elevation.

The invention is described and shown in the drawings as applied to a Remington typewriter, more specifically known as a "Model 17" or "Remington KMC." The typewriter mechanism with the exception of those parts illustrated in this application is substantially similar to the structure shown in Patents Nos. 2,289,531, July 14, 1942; 2,304,216, December 8, 1942; 2,326,312, August 10, 1943; and U. S. application, Serial No. 66,672, filed December 22, 1948, now U. S. Patent No. 2,579,763, in view of which only those portions of a typewriter are illustrated as are necessary to show the invention in association with related typewriter parts.

Portions of a conventional Remington typewriter, such as shown in the aforementioned patents and application, are illustrated in the drawings and include spaced parallel side frames which are connected at desired points by transversely extending bars, some of which are shown and will be hereinafter described. These side frames support the principal operating mechanism of the typewriter including the type action and key levers and according to the present invention also support the power driven roll. The conventional type guide 2 is mounted on type segment 3. Type segment 3 is mounted on transversely extending shift bar 4 vertically movable in guides at opposite ends carried by side frames 1 to provide the conventional case shift for upper

and lower case letters, as shown in Patent No. 2,289,531. A plurality of type bars 5 are pivotally mounted in type segment 3, only a central and an end type bar 5 being illustrated in Fig. 1 with the associated operating mechanism for each of these type bars. The usual type bar cushion 6 is suitably mounted on arms carried by type segment 3 for supporting the type bars in the position of rest. A transversely extending shaft 7 is rotatably mounted in side frames 1 and forms part of the segment shift mechanism.

A power driven roll 8 is rotatably mounted in transversely extending relation between the lower edges of side frames 1 toward the front portion thereof and is continuously rotated by suitable electric motor drive means which is not illustrated since this mechanism may be of any conventional type. Roll 8 has shaft extension rotatably mounted in bearings 9 in side frames 1, see Fig. 1. Roll 8 is formed of a tubular metal sleeve provided with a covering of resilient rubber or other suitable material to provide a cylindrical outer surface having good friction drive characteristics.

A fulcrum bar 10 is mounted in front of roll 8 and has a pair of supporting arms 11 secured to opposite ends thereof and extending around the front edges of side frames 1 and having the rear ends pivotally mounted on pivot screws 12 extending through apertures in side frames 1 and threadedly mounted in pivoted supporting brackets 13. Supporting brackets 13 are pivoted on studs 14 mounted on side frames 1. Studs 14 project inwardly from the front portions thereof and are located between pivot screws 12 and fulcrum bar 10 in a position closer to the fulcrum bar. Supporting brackets 13 have arms 15 projecting upwardly along the inner faces of side frames 1 with a set screw 16 at the upper end of each arm. Each screw 16 projects through enlarged apertures in one side of frame 1 with the head engaged on the outer face of the side frame. One of these supporting brackets 13 is mounted on the inner face of each side frame 1 to support arms 11 on opposite ends of fulcrum bar 10. This mounting for the fulcrum bar with apertures in side frames 1 substantially larger than the shanks of screws 12 carried by brackets 13, provide for adjustment of the pivotal mounting for arms 11 and fulcrum bar 10 so that the position of the axis for the pivotal mounting of fulcrum bar 10 may be changed with respect to the power operating mechanism of the typewriter for the purposes hereinafter described.

Fulcrum bar 10 is formed with a plurality of transverse spaced parallel slots in the upper edge for receiving and pivotally mounting a plurality of power arms 20 in spaced parallel relation on pivot rod 21 mounted on the fulcrum bar. Power arms 20 extend in transverse relation to power roll 8 rearwardly over the power roll. Each power arm 20 has a roller 22 mounted on the free rear end for engagement with cam projection 23 on type bar bell crank 24. Each bell crank 24 is pivotally mounted on rod 25 at the lower end. Rod 25 is carried by bell crank supporting bar 26 extending transversely across the lower portion of the typewriter and secured at opposite ends to side frames 1.

An anchor plate 27 is mounted on the lower edge of bell crank supporting bar 26 to provide an anchor along the front edge for power arm operating springs 28, one for each power arm 20 having one end anchored to plate 27 and the opposite end to the power arm in the rear of power driven

roll 8 for normally moving power arms 20 downwardly toward roll 8 about their pivots on rod 21. The rear edge of anchor plate 27 provides an anchor for one end of bell crank operating springs 29 having the opposite ends attached to rearwardly extending arms 30 on bell cranks 24. Springs 29 normally operate bell cranks 24 in a counter-clockwise direction, as shown in Fig. 2. A plurality of type bar operating links 31 each have one end secured to the upper end of a bell crank 24 and the opposite end pivotally secured to the lower end of one of a plurality of type bars 5. The type bars 5 are pivotally secured on type bar pivot rod 33 carried by type segment 3. Type bars 5 are arranged in the usual manner on type segment 3 for pivotal movement to have printing engagement with platen 34, Fig. 2, in the center position aligned with type guide 2 in a manner now well known in the art. An eccentric 35 for each power arm 20 is rotatably mounted on stub shaft 36 carried by the lower central portion of each power arm 20. Stub shaft 36 is arranged so that the smaller radius of the eccentric between the axis and the periphery will project below the lower edge of power arm 20 in a position to engage the periphery of power driven roll 8. The axis of stub shaft 36 on each power arm 20 is further arranged in the vertical plane through the axis of power driven roll 8 in substantially parallel relation so that each eccentric 35 is directly above roll 8. The eccentrics 35, as shown in Figs. 1 and 2, are of circular shape, but it will be understood that they may be of any other desired shape in outline. These eccentrics are in the form of discs which may be made from metal, plastic or other desired material. A length of radii between the shortest and longest radii of each eccentric 35 is selected to secure the desired movement of each power arm 20 on pivot rod 21 relative to power driven roll 8. The eccentrics are mounted on all of the arms in the same position and are of the same dimension so as to obtain a construction where all of power arms 20 are operated on their pivots to produce the same amount of arcuate movement in oscillation back and forth toward and from the power roll. It is conceivable that for power operation of some parts of the typewriter mechanism, eccentrics of different shape and size from the others may be used.

The mounting for fulcrum bar 10 on pivot screws 12 provides for the movement of fulcrum bar 10 for adjusting the position of the oscillating movement of power arms 20 relative to power roll 8 and bell cranks 24. Pivot screws 12 are positioned on side frames 1 in substantially coaxial relation with stub shafts 36 in the position of rest for power arms 20 as shown in Figs. 1 and 2. Fulcrum bar 10 may be moved up and down about the axis of stub shafts 36 and eccentrics 35, as shown in Figs. 1 and 2. This up and down movement of fulcrum bar 10 will move rollers 22 on the free ends of power arms 20 away from cam projections 23 of bell cranks 24 as the fulcrum bar 10 is moved upwardly and will be moved toward projection 23 when fulcrum bar 10 is moved downwardly. This provides for an adjustment of power arms 20 when they are moved in an upward direction by the operation of power roll 8 rotating eccentrics 35, to secure a greater or smaller amount of power operation of each bell crank 24 according to the position in which fulcrum bar 10 is adjusted. This varies the pressure of the impact of each type bar on the

platen in the printing operation so that either a greater or lighter pressure can be obtained by adjustment of fulcrum bar 10 for producing darker or lighter printing and also for producing a greater number of carbon copies as the impact pressure is increased.

The mechanism for securing this adjustment is shown in Figs. 1 to 4 inclusive. A cam plate 40 is mounted on transversely extending frame bar 41 secured at its ends to side frames 1. Cam plate 40 is formed with a slot 42 for receiving fulcrum bar adjusting cam 43 therein for free rotating movement. Cam 43 is rotatable on cam stud 44 threadedly mounted in the central portion of fulcrum bar 10. Cam 43 has a fulcrum bar adjusting handle 45 mounted on the rear side thereof in the rear of cam plate 40 and in front of fulcrum bar 10, as shown in Figs. 2 and 3.

When handle 45 is rotated in a clockwise direction, as shown in Figs. 1 and 4, fulcrum bar adjusting cam 43 operates in slot 42 to move fulcrum bar 10 upwardly to reduce the extent of the power operating stroke of the type bar bell cranks and adjust power arms 20 into the position shown in Fig. 3. When handle 45 is moved from the full line position as shown in Figs. 1 and 4, to the dotted line position as shown in Fig. 4, by movement in a counter-clockwise direction, fulcrum bar 10 is moved downwardly from the position shown in Fig. 3 to that shown in Fig. 2, so that the rollers 22 are closer to cam projections 23 on the type bar bell cranks to secure the full power operation of bell cranks by power arms 20 for obtaining a maximum impact pressure of each type bar 5 against platen 34. Handle 45 may obviously be adjusted to any intermediate position between the full and dot and dash positions shown in Fig. 4 to secure varying degrees of impact pressure of the type bars against the platen.

The operation of each power arm 20 is controlled by a trip mechanism forming part of each power arm assembly. Each trip mechanism controls the power arm and eccentric in the starting position or position of rest as shown, for example, in Figs. 2 and 5 which is referred to in the description herein as the No. 1 position. This trip mechanism is also controlled and operated by a trigger mechanism in turn controlled and operated by manual operation of a key lever. A separate power arm, trip mechanism, trigger mechanism and key lever is provided for each type action or other actuated device which it is desired to control from the keyboard of the machine. The construction and operation of one trip mechanism will serve to describe all of the trip mechanisms and the same applies to the description of the construction and operation of each type bar and trigger mechanism, all of which are made in the same manner for each power arm 20.

The trip mechanism, as shown in Figs. 1 to 6 inclusive, has a trip lever 46 pivoted at one end on stud 47 carried by depending arm 48 forming part of power arm 20. The opposite end of trip lever 46 is formed to provide a hook-shaped retaining finger 49 positioned to engage a laterally extending pin 50 carried by eccentric 35. The position of pin 50 and hook-shaped retaining finger 49 is arranged to arrest rotation of eccentric 35 in the position shown in Fig. 2 where the portion of eccentric 35 having the shortest radius is positioned toward power roll 8. This position of trip lever 46 is determined by a stop arm 51 formed on the same end of trip lever 46 as finger 49 for engagement with stop pin 52 mounted on

power arm 20. A tension spring 53 has one end secured to power arm 20 adjacent stop pin 52, as shown in Fig. 2, and the opposite end attached to lateral projection 54 on trip lever 46 at the end mounted on stud 47. Tension spring 53 normally operates trip lever 46 in a counter-clockwise direction, as shown in Fig. 2, for positioning hook-shaped retaining finger 49 in position to engage laterally extending pin 50 and stop rotation of eccentric 35. This position is determined by stop arm 51 engaging stop pin 52 limiting the motion of trip lever 46 in a counter-clockwise direction by the operation of tension spring 53 as shown in Fig. 2.

15 Trip lever 46 at a point intermediate its mounting on stud 47 and the end formed with hook-shaped retaining finger 49 is formed with a laterally extending trip arm 55 for engagement by the trigger mechanism to be described. It will be noted that trip arm 55 and depending arm 48 are located in front of or to the right of power driven roll 8 as shown in Fig. 2. A toggle link 56 is pivotally mounted at one end on pin 57 fastened to the terminal portion of trip lever 46 at the opposite side of pivot stud 47 from retaining finger 49 and in substantial alignment with the horizontal plane of the axis of stud 47. Toggle link 56 has the opposite bifurcated end engaged over supporting rod 58 carried by the lower rear edge of fulcrum bar 10. The bifurcated end of each toggle link 56 extends into a slot in the lower edge of fulcrum bar 10 as shown in Fig. 2, while the end pivoted on pin 57 is provided with an angularly extending stop finger 59 arranged to engage the lower end of depending arm 48 to limit clockwise movement of toggle link 56 on pin 57, as shown in Fig. 2.

20 Toggle link 56 operates in cooperation with trip lever 46 for controlling the downward movement of power arm 20 or the counter-clockwise rotation thereof about pivot rod 21 as shown in Fig. 2. The position of power arm 20 in the position of rest or No. 1 position is controlled by toggle link 56 with the parts ready for release to produce a power operation of one of the type bars or other power operated device. The toggle link 56 cooperates with the end of trip lever 46 on which it is mounted to provide a toggle that is arranged on dead center when power arm 20 is in the position of rest ready to be released for power operation of a type action as shown in Fig. 2. Tension springs 28 and 53 operate the trip mechanism and power arm to retain toggle link 56 with the portion at the bottom of the bifurcation engaged with supporting rod 58 as shown in Fig. 2, and trip lever 46 having stop arm 51 engaged with stop pin 52. This position of rest or No. 1 position for the power arm and trip mechanism controlled by the pivotal movement of trip lever 46 and toggle link 56 provides for the support of the power arm with its eccentric 35 so that the periphery of eccentric 35 is slightly spaced from the periphery of power roll 8. This position and the spacing of the eccentric from the power roll in the position of rest relative to power driven roll 8 is obtained by the adjustment of pivoted supporting brackets 13. By moving supporting brackets 13 so that the rear ends carrying pivot screws 12 are moved upwardly, the space between the periphery of the eccentrics and the power roll will be increased. The space between the eccentric and the power roll will be decreased as the adjustment on the rear ends of brackets 13 is made through moving them downwardly. The

desired adjustment is retained by tightening set screw 16.

The trigger mechanism has a trip rocker 65 provided for each power arm and trip mechanism. Each trip rocker 65 has the central portion formed to pivotally engage on rocker pivot rod 66. Rocker pivot rod 66 is rigidly secured to side frames 1 at opposite ends. Rocker comb plate 67 is slotted at intervals to receive and mount the plurality of trip rockers 65, one in each slot, in spaced parallel and aligned relation with each trip mechanism and power arm assembly. Rocker comb plate 67 has the upper edge secured to the bottom face of frame bar 41. The lower slotted margin of plate 67 is formed to engage around rocker pivot rod 66 for retaining trip rockers 65 in the desired spaced relation on pivot rod 66 and to further aid in supporting the pivot rod. A trigger 68 is pivotally mounted at its lower end at 69 on the rear end of trip rocker 65 and has an aperture 70 receiving pin 71 in laterally projecting relation. Pin 71 is mounted on the rear central portion of trip rocker 65 for limiting the pivotal movement of trigger 68 thereon. Ear 72 provides an anchor for one end of a tension spring 73 having the other end attached to depending arm 74 on the rear end of trip rocker 65. Spring 73 normally operates trigger 68 in a counter-clockwise direction as shown in Fig. 2 for engaging the lower portion of the trigger forming aperture 70 with pin 71, see Figs. 2 and 5. This spring 73 normally retains trigger 68 in a position so that shoulder 15 on the upper end will be normally positioned just below trip arm 55. Trigger 68 will thus be in position for moving trip lever 46 upon depression of a key lever. A finger 76 adjacent shoulder 15 forms the upper portion of trigger 68 and extends in front of trip arm 55 for cooperation with the shoulder and to retain trip arm 55 engaged thereon during the entire upward operative movement of the trigger.

A tension spring 77 is secured at one end to the lower rear intermediate portion of trip rocker 65 and has the opposite end secured to spring anchor 78. Spring anchor 78 is in the form of a sheet metal strip mounted on and projecting forwardly from key lever supporting bar 79. Key lever supporting bar 79 extends transversely between opposite side frames 1 and has the opposite ends rigidly secured thereto.

It will be understood that a trip rocker and trigger assembly, as above described, is provided for each power arm, a plurality being arranged in spaced parallel relation below each power arm in the position illustrated in the drawings. Each trigger assembly is associated with a power arm and trip mechanism so that a trigger mechanism is provided for controlling and operating each power arm.

A plurality of key levers 85, corresponding in number to the number of type bars and other mechanism for key lever operation, are provided at the front of the machine to form a keyboard having the key caps on each of the key levers arranged in one of a plurality of rows in a manner well known in the art. The rows of key caps on key levers 85 are positioned for manual operation in the usual and well-known manner. The rear ends of all the key levers are pivotally mounted on key lever pivot bar 86 carried by key lever pivot plate 87. Key levers 85 extend forwardly from pivot bar 86 in spaced parallel relation controlled by the spacing of the slots in plate 87. Key levers 85 extend between adjacent trig-

ger assemblies and trip rockers 65, see Figs. 1 and 2. The key levers each extend forwardly and have the key caps on the upwardly extending ends to form the usual keyboard of the typewriter. A key lever comb plate 88 has the upper edge mounted on frame bar 41 and the lower portion slotted to receive, guide and limit the vertical movement of key levers 85 in their spaced parallel relation. A rebound cushion strip 89 is mounted on the front face of comb plate 88 for limiting the upward movement of the key levers and forming a noise reducing stop. The downward movement of each key lever is limited by an adjustable stop on the lower portion of the comb plate. Each key lever is formed with an upwardly projecting ear 90 in the rear of comb plate 88 carrying a laterally extending pin 91 engaged over the upper edge of the forwardly extending arm of a key lever trip rocker 65, as shown in Fig. 2. Tension spring 77 in operating trip rocker 65 in a counter-clockwise direction as shown in Fig. 2, also serves to operate the key lever having pin 91 engaged therewith in a counter-clockwise direction to normally retain the corresponding key lever against cushion stop 89 in the position of rest, as shown in Fig. 2.

In the operation of a typewriter constructed as shown in Figs. 1 to 6 inclusive, manual depression of a key lever 85 will move pin 91 downwardly as shown in Fig. 2 in clockwise rotation of key lever 85 about its pivot. This will move the forwardly projecting end of key lever trip rocker 65 downwardly and rotate the trip rocker in a clockwise direction raising the rear end thereof. The raising of the rear end will move trigger 68 to engage shoulder 15 with trip arm 55 of trip lever 46.

With particular reference to Figs. 5 and 6 it will be seen that in the upward movement of trigger 68 engagement of shoulder 15 with trip arm 55 will then start movement of trip lever 46 in a clockwise direction. As the lever moves from the position of rest, the No. 1 position, Fig. 5, the end of hook shape retaining finger 49 will move eccentric 35 in a clockwise direction from the full line position in Fig. 5 to the dot and dash line position as finger 49 disengages from laterally extending pin 50. Trip lever 46 in the further operation of trigger 68 by depression of the key lever moves to the dot and dash line position shown in Fig. 5, designated position No. 2. In this movement of trip lever 46 to the No. 2 position shown in dot and dash lines, pin 57 carrying toggle link 56 will move out of the plane connecting the axis of stud 47 and supporting rod 58 into the dot and dash line position shown in Fig. 5, to break the toggle and produce counter-clockwise or downward movement of power arm 20 into the dot and dash line position, that is the No. 2 position. This downward movement is caused by the tension of power arm operating spring 28 which engages the periphery of eccentric 35 with continuously rotating power driven roll 8.

The moment the periphery of eccentric 35 engages power driven roll 8, rotating in a clockwise direction, as shown in Fig. 5 and indicated by the arrow, it will start eccentric 35 rotating in a counter-clockwise direction about its stub shaft 36. When eccentric 35 has been rotated about 90 degrees from the dot and dash line or No. 2 position, as shown in Fig. 5, the eccentric will have moved power arm 20 upwardly to some extent into the position shown in dot and dash lines designated as No. 3 in Fig. 6. When the

power arm and eccentric have reached this No. 3 position and the key lever is held manually depressed, trip arm 55 will be moved along shoulder 75 to a point where it is ready to disengage from the free end of the shoulder, as shown in dot and dash lines in Fig. 6. The immediate further movement of eccentric 35 and power arm 20 from the No. 3 position shown in Fig. 6, will allow trip arm 55 to disengage from shoulder 75 whereupon it will immediately move to the position shown in full lines in Fig. 6 under operation of tension spring 53.

As the rear end of power arm 20 moves upwardly through the operation of eccentric 35, roller 22 will engage cam projection 23 on type bar bell crank 24 and move it in a clockwise direction. In this power operation of a type bar bell crank 24, a type bar 5 will be power actuated to engage the type on the free end thereof with platen 34. As the power arm is operated by the eccentric from the No. 2 position shown in Fig. 5, to the No. 3 position shown in Fig. 6, roller 22 will engage cam projection 23 and start the power operation of a type bar 5. This power operation will continue through the operation of power arm 20 by eccentric 35 until the eccentric is rotated into the position shown in Fig. 6 in full lines where the portion of greatest radius is positioned between stub shaft 36 and power driven roll 8. This full line position of Fig. 6 is designated the No. 4 position and is the limit of power operation of bell crank 24 by power arm 20 through engagement of roller 22 with cam projection 23 on the bell crank.

According to the adjustment of the position of fulcrum bar 10 by fulcrum bar adjusting cam 43, power operation of a bell crank by an operating arm 20 into the No. 4 position will be varied so that the type bar will be moved by power operation of operating arm 20 to an angular position in advance of the platen varying from about 15 to 35 degrees. From this varied angular position determined by the adjustment of fulcrum bar 10 by adjusting cam 43, the type bars are given the desired amount of inertia for moving through the remaining arc and distance to engage the type on the free end of the type bar with the platen, or a sheet, or sheets of paper, engaged about the platen to secure the desired printing operation. As fulcrum bar adjusting cam 43 is operated to move fulcrum bar 10 downwardly as shown in Fig. 2, the power operation of a type bar is obtained through a greater angle and into a position closer to the platen than when the fulcrum bar is adjusted to its upper position. As the type bar is power actuated to a smaller angle in advance of the platen, the inertia applied to the type bar is greater and the impact of the type with the platen or paper thereon will be greater to secure a heavier impression. The heavier impression or impact of the type bar against the platen is used for obtaining a larger number of carbon copies while it is found that power operation of a type bar to a greater angle from the platen, such as 30 or 35 degrees, will reduce the impact of the type with the platen and provide a better adjustment for securing a clear impression where only one or a few typewritten copies are desired.

From the position of the parts, as shown in the No. 4 full line position in Fig. 6, the operation of power arm 20 continues through rotation of eccentric 35 by continuously rotating power roll 8 until eccentric 35 completes one revolution. Fig. 6 shows trip lever 46 in full lines in a position

where it has become released from trigger 68 with trip lever 46 rotated in a counter-clockwise direction until its movement is arrested by engagement of stop arm 51 with stop pin 52. This movement of trip lever 46 also moves the toggle from the broken position shown in dot and dash lines in Fig. 5, position No. 2, back to a position where the toggle is straightened. Operating arm 20 will move downwardly under the action of tension spring 28 with continued rotation of eccentric 35 until laterally extending pin 50 again engages hook-shape retaining finger 49. As this movement from the No. 4 position in Fig. 6, back to the position shown in Figs. 2 and 5 in full lines forming the No. 1 or starting position, takes place trip arm 55 will move downwardly below shoulder 75 on trigger 68. The trigger and key lever controlling it hold the trigger in the raised position and the depressed position of the key lever. As operating arm 20 moves downwardly and laterally extending pin 50 engages finger 49, toggle link 56 will move from the full line, No. 4 position, shown in Fig. 6, into the position shown in Figs. 1 and 5 forming the No. 1 position, where the portion of the toggle link 56 at the bottom of the bifurcated end will engage supporting rod 58 and limit downward movement of operating arm 20. This limiting of the downward movement of operating arm 20 will limit downward movement of arm 20 so that eccentric 35 will disengage power roll 8 as laterally extending pin 50 engages retaining finger 49.

This restores the power operating mechanism to the starting or No. 1 position. With this operation of the trigger, trip mechanism, power arm 20 and eccentric 35 from power roll 8, it will be seen that a repeat operation for one depression of a key lever cannot be obtained due to the disengagement of trip arm 55 from shoulder 75 on trigger 68 while a key lever is held in depressed position. The operation of the power arm, trigger and trip mechanism is very rapid. The operation is so rapid that unless provision is made for trip arm 55 to disengage from the trigger mechanism, it would be difficult to manually operate a key lever without securing more than one operation of the type bar controlled thereby. It should therefore be understood that for each depression of a key lever only one type bar operation will be secured with power operation of an arm 20.

As soon as a depressed key lever is released it will move back to its initial starting position. In this movement trigger 68 will have the left-hand edge portion below shoulder 75 engage the right-hand portion of trip arm 55. Trigger 68 will slidably move along trip arm 55 until shoulder 75 moves below the trip arm when it will move into the starting or No. 1 position, as shown in Figs. 2 and 5, in full lines. This movement of trigger 68 back to the starting position in engagement with trip arm 55 causes trigger 68 to move on its pivot on trip rocker 65 against the tension of spring 73. Trigger 68 will rotate in a clockwise direction, as shown in Figs. 2 and 5, for example, in this return movement to the starting position so that the lower portion of the trigger normally engaged with pin 71 will move away from the pin. Aperture 70 is sufficiently larger than pin 71 to provide for this movement of the trigger so that shoulder 75 can ride along trip arm 55 into the starting position. As the shoulder 75 disengages from arm 55 in the return movement of a key lever to starting position, trigger 68 will be operated by spring 73 in a counter-clockwise direction until it reaches the full line position, as shown in

Fig. 5, forming the No. 1 position, or position of rest.

Fig. 1 shows a central and an end type bar, type bar bell crank and operating link construction illustrating the usual differences in the construction and mounting of an end type bar and bell crank from a corresponding central type bar and bell crank. The corresponding power operating structure is also shown associated with both the center and end type bar mechanisms to illustrate how power operating mechanism operates the several type bars. With this variation in the construction of the type bars and bell cranks it will be understood that all of the power arms are identical and secure an operation of the several type bars to produce the desired impact with the platen in a manner to obtain uniform impact between each of the type bars and the platen.

A modified form of power arm, trip and trigger mechanism is illustrated in Figs. 7 to 11. Only one of the power arm assemblies will be described in view of the fact that all of the power arm assemblies used for operating the several typing or other devices in the typewriter will be duplicates. Each power arm 95 has the right-hand end as shown in Fig. 7, formed with an aperture to engage on pivot rod 21 carried by fulcrum bar 10 for pivotally mounting one end of the power arm in a slot formed in the upper edge of the fulcrum bar. Each of these modified power arm constructions is formed to be interchangeably mounted in fulcrum bar 10 for operation by power driven roll 8 to operate bell cranks 24 in the same manner as the power arms 29, shown in Figs. 1 and 2. The rear end of each power arm 95 carries a roller 96 similar to roller 22 for engaging cam projection 23 on a bell crank 24 for power operation of bell crank 24 in the upward movement of the rear end of power arm 95. Power arm operating springs 28 have the upper ends attached to power arms 95 at the rear end portion thereof for normally moving each power arm 95 downwardly to its limit position.

Power arm 95 has a depending portion 97 formed with a foot 98 extending forwardly at the lower rear face of fulcrum bar 10 for engaging stop bar 99 mounted on the rear face of fulcrum bar 10. Stop bar 99 limits the movement of power arm 95 in a counter-clockwise direction, as shown in Figs. 7 and 10. The thickness of this plate determines the limit of movement of power arm 95 toward power driven roll 8 and this position may be varied by changing the thickness of plate 98, or by using shims between plate 98 and fulcrum bar 10.

An eccentric slide 100 has the rear end formed with a slot receiving slide pin 101 projecting laterally from the rear end portion of power arm 95. One side of eccentric slide 100 is slidably engaged against an adjacent face of power arm 95 throughout the central portion thereof. Power arm 95 is formed with an aperture opposite the rear end of eccentric slide 100 to accommodate an eccentric slide operating spring 102 having one end connected to the rear end of eccentric slide 100 in the slotted portion thereof and the opposite end secured to power arm 95. Operating spring 102 is a tension spring normally operating slide 100 to move it so that pin 101 limits the rearward movement at the forward end of the slot formed therein. An eccentric 103 is mounted on the side of slide 100 opposite to arm 95 and has a cylindrical boss 104 projecting from the side adjacent power arm 95 in concentric relation to the periphery thereof rotatably engaged in an aperture in eccentric slide 100. A

stub shaft 105 rotatably mounts eccentric 103 with one end rigidly secured to power arm 95 in the central portion directly above and in spaced parallel relation with the axis of power roll 8. The outer free end of stub shaft 105 is formed with a flanged head for retaining eccentric 103 on the stub shaft with eccentric slide 100 between the inner face of the eccentric and power arm 95. In this way eccentric slide 100 is assembled with eccentric 103 on power arm 95 and arranged so that tension spring 102 will normally operate to pull the slide to the left, as shown in Figs. 7 to 10 for normally rotating the eccentric into a position where the portion having the longest radius between the axis and the periphery will extend toward the rear or left-hand end of eccentric slide 100 as the parts are shown in Figs. 7 to 10.

The right-hand end of eccentric slide 100 carries a trip lever 106 pivotally mounted thereon intermediate its ends.

Trip lever 106 has a guide projection 107 rotatably mounted on the lower end thereof and projecting from the side adjacent power arm 95 into the elongated vertical slot 108 formed in power arm 95 and the depending portion 97 thereof. Trip lever 106 is formed with a laterally extending trip arm 109 at the upper end portion thereof and another laterally extending check arm 110 at the upper extremity thereof. Check arm 110 is offset to the left of trip arm 109, as shown in Figs. 7 and 10.

A trigger 111 has a laterally extending trigger arm 112 at the upper extremity extending toward power arm 95 and positioned for engaging trip arm 109 and check arm 110 depending upon the position of trip lever 106. Trigger 111 has a slot formed in an intermediate portion thereof receiving guide projection 107 slidably guiding trigger 111 for relative vertical sliding movement on power arm 95. The lower end of trigger 111 is pivotally mounted on the rear end of trip rocker 114 having its center portion rotatably mounted on rocker shaft 115 carried by a slotted supporting plate mounted on the rear face of frame bar 41 of the typewriter frame extending between side frames 1.

Key levers 116 have upwardly extending portions at the forward ends carrying the key caps and have the rear ends pivotally mounted on key lever pivot bar 86 carried by pivot plate 87 mounted on key lever supporting bar 79 of the typewriter frame structure, as hereinabove described. The comb plate 88 also guides the forward ends of key levers 116 in the same manner hereinbefore described. Key lever 116 has a projection extending upwardly therefrom carrying laterally extending operating pin 117 engaged over the upper edge of the forwardly extending arm of trip rocker 114. A tension spring 118 has one end secured to the rear end portion of the trip rocker and the opposite end secured to the rear end portion of key lever 116. Tension spring 118 normally operates to rotate both key lever 116 and trip rocker 114 in a counter-clockwise direction for holding these parts in their position of rest or starting position, heretofore described as the No. 1 position. This position of the parts is shown in Fig. 7, in which eccentric 103 is held with its shorter axis directed toward power driven roll 8 in spaced adjacent relation to the periphery thereof through trigger 111 having trigger arm 112 engaged with trip arm 109 and foot 98 engaging stop bar 99. In this position eccentric slide 100 is held in a pos-

tion where trip lever 106 is at the upper limit of its movement in slot 103 with cylindrical boss 104 having its axis directly above the axis of stub shaft 105. In this position of the parts tension spring 102 is under substantial tension with pin 101 positioned in the central portion of the slot in eccentric slide 100. Trigger 111 is at the lower limit of its movement as indicated by guide pin 113 engaged with the trigger at the upper end of the slot.

By depressing key lever 116, trip rocker 114 is moved in a clockwise direction from the position shown in Fig. 7, to that shown in Fig. 8, for moving trigger 111 upwardly relative to power arm 95 until pin 113 is located in the lower portion of the slot formed in the trigger. This disengages trigger arm 112 from trip arm 109. As soon as trigger arm 112 disengages trip arm 109, spring 102 operates eccentric slide 100 toward the left from the position shown in Fig. 7 to that shown in Fig. 8 for rotating eccentric 103 until the periphery engages power roll 8. As soon as the periphery of eccentric 103 engages the power roll, which takes place in the position of the parts shown approximately in Fig. 8, providing what may be termed the No. 2 position of the parts in a cycle of operation, the power roll rapidly rotates the eccentric. As the eccentric rotates on stub shaft 105 cylindrical boss 104 in cooperation with pin 101 moves trip lever 106 downwardly in slot 103 from the position shown in Fig. 7 to the position shown in Fig. 8 and thereafter the downward movement continues to the position shown in Fig. 9. In this operation of eccentric 103 from the No. 2 position to the No. 4 position shown in Fig. 9, and corresponding to the similar position shown in Figs. 5 and 6, eccentric 103 is moved until its portion of maximum radius between the stub shaft axis and the periphery is in downwardly extending relation engaged with power roll 8. In this operation of eccentric 103 by the power roll, power arm 95 is moved from the lower position shown in Figs. 7 and 8, to its upper position of movement in the power operating stroke for engaging cam projection 23 on bell crank 24 and producing a power operation of a type bar as hereinabove described for printing a character on paper placed about the typewriter platen.

From the No. 4 position shown in Fig. 9, power roll 8 continues to rotate eccentric 103 to complete one revolution about stub shaft 105. During this continued rotation of eccentric 103, the right-hand end of eccentric slide 100 with trip lever 106 moves upwardly in slot 103 relative to power arm 95. With the key lever held in depressed position as shown in Figs. 8 to 10, trigger 111 is held in its uppermost position during this power operation of power arm 95 by the eccentric. As the eccentric completes its revolution about stub shaft 105, trip lever 106 is moved into a position where check arm 110 will engage to the right of, or behind trigger arm 112. As eccentric 103 and eccentric slide 100 reach this position, eccentric 103 becomes disengaged from power roll 8 and cylindrical boss 104 is moved so that its axis is substantially above stub shaft 105 whereupon spring 102 tends to operate eccentric slide 100 to the left as shown in Fig. 10. Foot 98 engages stop bar 99 and limits downward movement of power arm 95.

As soon as key lever 116 is released so that it will be returned to its upper normal position of rest, as shown in Fig. 7, trigger arm 112 will disengage check arm 110 by downward movement

relative to trip lever 106. Spring 102 will then operate eccentric slide 100 and trip lever 106 to engage trip arm 109 with trigger arm 112 restoring the parts to the position shown in Fig. 7.

5 Check arm 110 cooperates with trigger arm 112 for retaining eccentric slide 100 against operation by spring 102 to reengage eccentric 103 with power roll 8 and prevent a repeat operation of the power arm and type bar actuated thereby.

10 In other words, the cooperation between trigger 111 and trip lever 106 with the respective trip arm 109 and check arm 110 controls operation of the power arm so that only one type bar actuation is obtained for each depression of a key lever 116. It will be noted that in operation from the positions shown in Figs. 7 to 10, trip lever 106 oscillates about guide projection 107 so that the upper end moves in a counter-clockwise direction from the position of Fig. 7 to the position of

15 Fig. 9. This movement of the upper end of trip lever 106 continues for moving check arm 110 to the right of trigger arm 112 for engaging it behind the trigger arm to limit spring operated movement of eccentric slide 100.

20 Fig. 12 shows another modification of the invention in which the power arm and trigger assembly is constructed in the same manner as shown in Figs. 1 to 6 inclusive. The structure of the trip lever is slightly modified in Fig. 12 from that hereinbefore described. This modification provides a trip lever 120 pivoted on a stud 121 carried by power arm 122 of substantially duplicate construction to power arm 28. The upper end of trip lever 120 is formed with a hooked-

25 shape portion for retaining eccentric 123 against rotation on the power arm. The trip lever at the opposite side of stud 121 from the portion engaging eccentric 123 rotatably mounts a toggle roller 124 having peripheral rolling engagement with toggle plate 125 jointly secured on the rear facet of fulcrum bar 126 with spring anchor member 127. A tension spring 128 has its upper end connected to spring anchor 127 and its lower end secured to a lateral projection on trip lever 120 for normally rotating the trip lever in a counter-clockwise direction as shown in Fig. 12.

30 The axis of toggle roller 124 in the position of rest or starting position of the trigger mechanism, trip lever and power arm, lies in the horizontal plane with the axis of pivot stud 121. This provides for the support of power arm 122 with the peripheral portion of eccentric 123 having the shortest radius arranged in adjacent but spaced relation to the periphery of power roll 8, as shown in Fig. 12. The modification consists principally in providing roller 124 as a substitute for the toggle link of Figs. 1 to 6. Whenever the trigger mechanism operates trip lever 120 in the manner hereinabove described in connection with

35 Figs. 1 to 6, roller 124 will move downwardly along toggle plate 125 and shorten the distance between plate 125 and the axis of stud 121. This produces downward movement of power arm 122 under the operation of the spring 128 connected to the rear end of the power arm, as diagrammatically illustrated in Fig. 12, for engaging the periphery of eccentric 123 with the periphery of power roll 8 after trip lever 120 has disengaged the pin carried by the eccentric. Since the operation of a trip lever like 120 is fully explained in the description of operation of the structure shown in Figs. 1 to 6 inclusive, it should be clearly understood how the structure shown in Fig. 12 will complete a cycle of operation to produce a power operation of a type bar through one revolution.

tion of rotation of eccentric 139 about its pivotal mounting on power arm 122.

A further modified construction of the power arm and trip lever mechanism is shown in Figs. 13 and 14. Figs. 13 and 14 illustrate opposite sides of the power arm without showing the mounting on the fulcrum bar and other associated parts in view of the fact that the power arm assembly of these figures can be substituted for the corresponding parts shown in Figs. 1 to 5. This modified power arm construction comprises a pair of sections having a pivot section 130 and an operating arm section 131. Pivot section 130 has an aperture 132 for receiving pivot rod 21 to pivotally mount the right-hand end of the power arm on the fulcrum bar. The central portion of arm section 131 is pivoted on stud 133 mounted on the end of pivot section 130 opposite the end having aperture 132. The right-hand end of arm section 131, as shown in Fig. 13, is secured to the opposite end portion of pivot section 130 by means of eccentric stud 134. Eccentric stud 134 has a head engaging the outer face of arm section 131 on one side, as shown in Fig. 14, and a cylindrical portion extending through an aperture in the end of arm 131 and engaging the adjacent face of pivot section 130 in endwise relation over slot 135 formed in section 130. A lock screw 136 has the head thereon engaging the opposite face of pivot section 130, as shown in Fig. 13, from that engaged by the end of eccentric stud 134, with the shank extending through slot 135 and having a smaller diameter than eccentric stud 134. The end of the shank of lock screw 136 is threaded in eccentric relation in eccentric stud 134 for tightly securing stud 134 against rotation relative to pivot section 130 and also tightly securing the right-hand end of operating arm section 131, as shown in Fig. 13, to section 130 against relative movement. By loosening lock screw 136, eccentric bolt 134 may be rotated to move the right-hand end of operating arm section 131, as shown in Fig. 13, up or down for adjusting the position of the free end of arm section 131 relative to the plane extending through the axis of aperture 132 and pivot stud 133. The free end of operating arm section 131 carries a roller 137 similar to roller 22, as shown in Fig. 1, positioned for engaging and operating a type bar bell crank. The position of roller 137 on each power arm of a series for operating the typing and other devices may be adjusted relative to each other by adjusting the position of roller 137 relative to the plane through stud 133 and aperture 132 by the rotation of eccentric stud 134.

A stub shaft 138 is mounted on pivot section 130 with its axis in spaced parallel relation above power driven roll 8. An eccentric 139 having a cam shaped periphery is rotatably mounted on stub shaft 138 in a position to have its periphery engage the periphery of power driven roll 8. The inner marginal portion of eccentric 139 is recessed to provide angular shoulder portions 140 formed to receive the retaining finger 141 on one end portion of trip member 142 pivoted at the opposite end at 143 on pivot section 130 of the lower arm. Trip member 142 has another portion of the first-mentioned end extending in angular relation to retaining finger 141 and formed with trip finger 144 positioned to engage stop pin 145 mounted on pivot section 130 at the lower end of trip member 142 for limiting the clockwise movement of trip member 142 about its pivot 143, as shown in Fig. 13. This limit position deter-

mines the position of retaining finger 141 where it engages in the recessed portion of eccentric 139 having the shouldered portions 140.

A trip lever 146 has its lower end pivotally secured on stud 147 mounted on the lower depending portion of pivot section 130, while the upper end portion is formed with a trip projection 148 positioned to engage trip finger 144 below stop pin 145 for moving trip member 142 in a counter-clockwise direction as shown in Fig. 13 in the clockwise movement of trip lever 146. A tension spring 149 has one end secured to a laterally projecting portion of trip lever 146, as shown in Fig. 13, while the opposite end is secured to an ear extending laterally from trip member 142. This spring normally rotates trip lever 146 in a counter-clockwise direction and trip member 142 in a clockwise direction, as illustrated in Fig. 13, to engage trip finger 144 with stop pin 145 for limiting movement of trip member 142 by the spring. The movement of trip lever 146 is also limited by stop projection 150 extending through an aperture in pivot section 130 and engaging a portion of pivot section 130 forming the edge of the aperture.

A portion of the trip lever on the opposite side of pivot stud 147 from that part formed with trip projection 148 pivotally mounts toggle link 151 thereon by means of pivot stud 152. Trip lever 146 is formed with a laterally extending trip arm 153 between trip projection 148 and stud 147 in a position for engagement by the trigger of the key actuated trigger mechanism as hereinabove described in connection with Figs. 1 to 6. Toggle link 151 is a duplicate of toggle link 56 as shown in Figs. 1 to 6, and cooperates with trip lever 146 to control the pivotal movement of the power arm in the same manner hereinbefore described.

With this construction as shown in Figs. 13 and 14, the depression of a key lever will operate the trigger to engage trip arm 153 and rotate trip lever 146 in a clockwise direction as shown in Fig. 13. Operation of trip lever 146 will operate trip member 142 in a counter-clockwise direction, as shown in Fig. 13, through engagement of trip projection 148 with trip finger 144 against the tension of spring 149. This operation of trip lever 146 and trip member 142 by the trigger will move retaining finger 141 out of the recess in eccentric 139 and break the toggle through toggle link 151 to provide counter-clockwise movement of the power arm sections 130 and 131 about the pivot on the pivot rod extending through aperture 132. This movement will bring the periphery of eccentric 139 upon release by retaining finger 141 into engagement with the periphery of power driven roll 8 to secure the power operation of the power arm for operating a type action or other device as hereinabove described. The trigger and trip arm 153 cooperate in the same manner heretofore described in connection with the structure shown in Figs. 1 to 6, inclusive, in preventing a repeat operation of the power arm and type action or other device during a single depression of a key lever. As eccentric 139 completes one revolution of operation by power roll 8, retaining finger 141 will engage in the recess with shouldered portions 140 as toggle link 151 cooperates with trip lever 146 to support the power arm in a position where the periphery of eccentric 139 has become disengaged from contact with the periphery of power roll 8.

Pivot section 130 is first adjusted to position the periphery of the eccentric in the desired

spaced relation to power driven roll 8. Then, by adjusting eccentric stud 134 operating arm section 131 may be adjusted relative to section 130 to change the position of roller 137 to the associated bell crank lever. This adjustment provides for the variation in the operation of the several bell cranks or other devices by respective power arms so as to change the character of type impression of one type action to another. By this adjustment uniform impacts of each type bar with the platen can be obtained to compensate for variations in dimension and tolerance between the parts of the power operating mechanism. This adjustment provides a simple means for obtaining uniformity of power operation of all of the independent type actions and other devices on the typewriter which are power operated through manual actuation of a key lever on the keyboard.

With the present invention a light pressure can be provided for manual key lever operation in which the downward movement of the key levers may be limited by key lever comb plate 88. Only sufficient force is required in depressing a key lever to operate the trigger and trip member to overcome the tension of the springs normally holding these members in the position of rest. After the trigger operates the trip member to release the eccentric and break the toggle or other means for retaining the eccentric out of engagement with the power driven roll, the operation of the various type actions and other devices in the typewriter is secured solely through power operation from the oscillating movement of each power arm by its eccentric from power driven roll 8. Each of the power arms and trip levers are assembled as a unit to form a power arm assembly while each trigger is connected with its rocker arm to form a trigger assembly with a key lever. This assembly mechanism provides a convenient sub-assembly feature that provides for economy in construction, assembly and servicing of a typewriter having this power operating mechanism.

A ribbon vibrator is operated in the power operation of each type bar and has the usual ribbon guide 155 slidably mounted on the rear side of type guide 2 in the usual manner. The lower end of ribbon guide 155 is pivotally connected to the forward end of supporting lever 156 having its rear end mounted on shaft 157 rotatable in bracket 158 suspended from supporting plate 159 secured to type segment 3 and movable therewith. One end of shaft 157 at the outer side of bracket 158 carries a selector arm 160 having an inverted T-shaped slot 161 formed in the free end thereof.

A universal shaft 162 is mounted at opposite ends on side frames 1 for oscillating movement and carries a universal bar 163 extending entirely across the typewriter between side frames 1 with one margin secured to universal shaft 162 and the opposite marginal portion engaged over rearwardly extending arms 30 of all of the type bar bell cranks 24. A rock arm 164 has one end secured to an intermediate portion of universal shaft 162 and extends in a direction opposite from universal bar 163 toward the rear of the typewriter with the rear end offset upwardly and bifurcated. The bifurcated rear end of rock arm 164 is engaged about a pivot stud 165 carried by rocker arm 166 rotatably mounted on the forwardly extending supporting arm 167 formed on the lower end of bracket 168 having the upper end detachably secured to shift bar 4 intermediate the ends thereof and forming part of the supporting structure for the vertically movable type

segment 3. A leaf spring 169 mounted on arm 167 has a pair of arms 170 and 171 arranged above and below rocker arm 166 for cooperation therewith to limit the rocking movement of the rocker arm during the operation of ribbon guide 155. A leaf spring 172 has one end mounted on bracket 168 and the opposite end engaged with universal bar 163 for normally rotating universal shaft 162 in a clockwise direction, as shown in Fig. 2, and maintaining universal bar 163 in engagement with rearwardly extending arms 30 of the type bar bell cranks.

Bracket 158 rotatably mounts shaft 173 in the lower end thereof carrying a laterally extending arm 174 on one end. Arm 174 has a guide pin 175 on the free end thereof. A vibrator link 176 has the lower end pivotally connected to rocker arm 166 at the end opposite from that carrying pivot stud 165 engaging rock arm 164. The upper end of vibrator link 176 is formed with a slot 177 slidably engaged with guide pin 175 carried by arm 174 while the upper terminal portion of the vibrator link has a laterally extending operating pin 178 engaged in the inverted T-shaped slot 161. Suitable manually operated means is connected with shaft 173 for rotating the shaft so that vibrator link 176 can have the operating pin selectively adjusted into either end of the horizontal portion of T-shaped slot 161 or aligned with intermediate and the vertically extending portions thereof. When link 176 has operating pin 178 aligned with the vertically extending portion of inverted T-shaped slot 161, the operation of the oscillator link will not vibrate the ribbon guide. This is used when the typewriter is to be used for stenciling and similar purposes where a ribbon is not employed during the typing operation. This mechanism for adjusting the position of the vibrator link and for moving the ribbon guide upwardly for each type bar operation is of substantially conventional design as used in the Remington typewriter with the exception that the bracket and rocker arm construction connected with the lower end of the vibrator link for operation by the type bar bell cranks is a new construction combined with the old construction so that the ribbon guide may be vibrated to move the ribbon into position to be engaged by the type on the type bars for printing in the usual manner. The construction shown facilitates the operation of the ribbon guide from the type bar bell cranks and forms a convenient construction for operating the ribbon guide in a power operated machine of the character disclosed herein.

Fig. 15 shows a modified form of trigger designated 180, similar to trigger 68. Trigger 180 has the shoulder and finger construction on the upper edge similar to trigger 68. Trigger 180 has a repeat projection 181 at the end of the shoulder opposite the finger for engaging and retaining trip arm 55 engaged on the shoulder. This projection 181 enables an operator by holding a key lever depressed to retain a trip lever on a selected power arm in a disengaged position relative to the eccentric with the toggle broken and the eccentric continually engaged with power roll 8. The power arm will be repeatedly oscillated to power operate the bell crank and power operate mechanism connected therewith. This repeat operation is used for controlling power operation of a carriage return and line space mechanism. By this repeat operation the carriage return and line space mechanism is power operated at the end of the carriage return movement to rapidly feed the paper into and out of the machine. It is

also useful to secure repeated operation of the underscoring type bar and any other typing or other devices on the typewriter where repeat operation may be desirable while a key lever is depressed.

The invention claimed is:

1. In a power operated typewriter having a power driven roll, a plurality of typing and other operated devices and a plurality of key levers, one for each typing and other operated device, the combination of a plurality of power arms pivoted at one end and each arranged to have the opposite end engage and operate one of said typing and other operated devices in pivotal movement thereof in one direction, a plurality of eccentrics, one eccentric rotatably mounted on each power arm for peripheral engagement with said power driven roll to move said power arm on its pivot in operating one of said devices, trip means including a plurality of trip levers, each pivotally mounted on one of said power arms and having a portion thereof latching the eccentric against rotation, trigger means for each power arm operating said trip lever to release said eccentric for engagement with and operation by said power driven roll for moving said power arm to operate one of said devices, and key lever actuated means for operating each of said trigger means to engage its trip lever and release its eccentric whereby each typing or other device is power operated by manual operation of the corresponding key lever.

2. A power operated typewriter as claimed in claim 1 wherein a fulcrum bar pivotally mounts said power arms at one end and is engaged by said trip means in holding said eccentric and power arm in inoperative position; and means for adjusting the position of said fulcrum bar relative to said power driven roll and said devices for varying the operation of said devices by said power arms.

3. A typewriter claimed in claim 1 having plural projections on said trip lever sequentially engageable by a shoulder on the trigger means for securing only a single operation of a typing or other device for each operation of a key lever.

4. A typewriter as claimed in claim 1, having said trip means for each power arm comprising a trip lever pivotally mounted on the power arm intermediate the ends, one end of said trip lever being formed into hook shape for engaging a stop pin on the eccentric carried by said arm and controlling rotation of said eccentric, the other end of said trip lever having means mounted thereon for engaging a fixed part of said typewriter and cooperating therewith to control movement of said power arm according to the position of said trip lever.

5. A typewriter as claimed in claim 1, having said trip means for each power arm comprising a trip member pivoted on said power arm having an end portion formed to engage a complementary portion on the eccentric and retain said eccentric against rotation, and toggle means engaged with said trip member and with a part on said typewriter fixed in position relative to the pivot for said power arm and controlling the pivotal movement of said power arm in one direction.

6. A typewriter as claimed in claim 1, having the trip means for each power arm comprising a trip member pivoted on said power arm having a portion formed to engage a complementary portion on the eccentric and retaining said eccentric against rotation, a trip member pivoted on said

power arm operable for engaging and moving said trip member, and a toggle link pivoted on said trip lever and engaging a part on said typewriter fixed relative to the pivot for said power arm and controlling the pivotal movement of said power arm in one direction.

7. A typewriter as claimed in claim 1, having the trip means for each power arm comprising a trip lever pivoted on said power arm having an end portion formed to engage a part on the eccentric and retain said eccentric against rotation, stop means for limiting pivotal movement of said trip lever, resilient means connected to said power arm and trip lever for normally moving said trip lever into eccentric retaining position, and a toggle link pivoted on said trip lever and engaging a part on said typewriter fixed relative to the pivot for said power arm and controlling the pivotal movement of said power arm in one direction.

8. A typewriter as claimed in claim 1, having the trip means for each power arm comprising a trip lever pivoted on said power arm with an end portion formed to control rotation of said eccentric, stop means for limiting pivotal movement of said trip lever on said power arm, resilient means connected to said power arm and trip lever for normally moving said trip lever into eccentric retaining position, a trip arm extending laterally from said trip lever intermediate the ends and engageable for moving said trip lever, and a toggle link pivoted on said trip lever and engaging a part on said typewriter fixed relative to the pivot for said power arm and controlling the pivotal movement of said power arm in one direction.

9. A typewriter as claimed in claim 1, wherein the trip means for each power arm comprises a pair of trip lever sections pivoted on said power arm, one section having a part engaging a part on the eccentric to hold said eccentric against rotation, each section having projections for engagement for pivotal movement of said one section by the other, a tension spring connecting said trip lever sections for normally moving said sections into one position where said one section engages said eccentric, stop means on each section for engaging said power arm and limiting pivotal movement, a trip arm on said other section engageable to operate both sections to disengage said one section from said eccentric, and a toggle link pivoted on said trip lever and engaging a part on said typewriter fixed relative to the pivot for said power arm and controlling the pivotal movement of said power arm in one direction.

10. A typewriter as claimed in claim 1, wherein the trip means for each power arm comprises a trip lever pivoted on said power arm with an end portion formed to control rotation of said eccentric, stop means for limiting pivotal movement of said trip lever on said power arm, resilient means connected to said trip lever for normally operating said trip lever in one direction to engage and retain said eccentric against rotation, a trip arm extending laterally from said trip lever intermediate the ends and engageable for moving said trip lever, and a roller rotatably mounted on the opposite end portion of said trip lever and engaging a part on said typewriter fixed relative to the pivot for said power arm and controlling the pivotal movement of said power arm in one direction in cooperation with said trip lever.

11. A typewriter as claimed in claim 1, wherein

the trip means for each power arm comprises a trip lever pivoted on said power arm having an end portion formed to engage a part on the eccentric and retain said eccentric against rotation, resilient means connected with said trip lever for normally rotating it into eccentric retaining position, and a roller on the opposite end of said trip lever engaging a part on said typewriter fixed relative to the pivot for said power arm and controlling the pivotal movement of said power arm in one direction in cooperation with said trip lever.

12. In a typewriter as claimed in claim 1, an eccentric slide, wherein said eccentric slide rotatably receives a part on said eccentric intermediate its ends, one end of said slide having a slideable pivot connection with said power arm, a trip lever mounted on the other end of said eccentric slide having a part on one end slidably engaged with said power arm, a trip arm extending laterally from the opposite end of said trip lever latchable by the trigger means to secure said slide against slideable movement, and resilient means connected to the power arm and eccentric slide for normally moving said slide in one direction and rotating said eccentric to engage the power roll upon release of the trip arm by operation of said trigger means.

13. In a typewriter as claimed in claim 1, an eccentric slide having an eccentric rotatably mounted thereon, and wherein the eccentric is provided with a cylindrical boss rotatably engaged in the central portion of the eccentric slide, said eccentric slide having one end provided with a slideable pivot connection to said power arm, a trip lever pivotally mounted on the opposite end of said eccentric slide, said trip lever being formed at one end for slidably engaging in a slot formed in said power arm and the opposite end formed with a laterally extending trip arm, resilient means connecting said power arm and eccentric slide for normally moving said eccentric slide in one direction to engage said eccentric with the power roll, and a trigger slidably latched with said power arm adjacent said trip lever having a laterally extending trigger arm for latching said trip arm to retain said eccentric slide in one position with said eccentric disengaged from the power roll.

14. A power operated typewriter comprising a power driven roll, a plurality of type actions, a plurality of power arms, one for each type action having one end positioned to engage one of said type actions, a plurality of eccentrics, one rotatably mounted on each power arm and positioned to have peripheral engagement with said power driven roll, a plurality of trip levers, each pivoted on one of said power arms and having an end engaging the eccentric on said power arm in one position for holding it against rotation, a fulcrum bar pivotally mounting said power arms at one end in spaced parallel relation, means on each of said trip levers engaging said fulcrum bar for cooperation in supporting said power arms in inoperative position with said eccentrics spaced from said power driven roll when said trip levers are engaged with said eccentrics, trigger means for each trip lever, and a plurality of key levers, one for each type action

and power arm for engaging said trigger means for one of said trip levers and operating said trigger means and trip lever to disengage said eccentric and move said power arm on its pivotal mounting on said fulcrum bar to engage the eccentric with said power roll for rotation to move said power arm to engage and operate one of said type actions.

15. A typewriter as claimed in claim 3, having said fulcrum bar movable coaxially to said eccentrics for adjusting the effective operation of said type actions by said power arms, and manually operable means for adjusting the position of said fulcrum bar.

16. A power operated typewriter comprising a power driven roll, a plurality of type actions, a plurality of power arms, one for each type action, a fulcrum bar having one end of each power arm pivotally mounted thereon, said arms extending transversely to said power driven roll and the opposite end of each arm being formed to engage one of said type actions, a plurality of eccentrics, each mounted on one of said power arms intermediate the ends in position to engage said power driven roll, a plurality of trip levers, each pivotally mounted on one of said power arms having one end formed to control rotation of said eccentric on said power arm and engagement with said power driven roll, toggle means on each of said trip levers cooperating with said fulcrum bar for limiting movement of each power arm and eccentric toward said power driven roll for supporting each arm and eccentric in spaced relation to said power driven roll controlled by said trip levers, a plurality of triggers, one for each trip lever, and a plurality of key levers, each positioned for operating one of said triggers to engage a corresponding trip lever and move it into disengaged position releasing said eccentric for movement into engagement with said power driven roll upon manual operation thereof whereby said power roll will rotate said eccentric and move said power arm to engage and operate a type action according to selected key lever operation.

17. A typewriter as claimed in claim 5 in which the toggle means cooperating with said fulcrum bar comprises a toggle for each power arm having one end connected to a trip lever and the opposite end engaged with said fulcrum bar.

18. A typewriter as set forth in claim 5, wherein each trip lever has a projection thereon latchable by a trigger shoulder, said shoulder releasable to unlatch said trip lever and release the eccentric for engagement with the power roll and said projection displaceable to a second latching position by the revolving eccentric to thereby limit said eccentric to one revolution.

FREDERICK W. SCHREMP.
